UNITED STATES PATENT OFFICE.

ELMER E. HUNT, OF CHICAGO, ILLINOIS.

WINDOW-VENTILATOR AND THE LIKE.

1,383,811.

Specification of Letters Patent. Patented July 5, 1921.

Application filed April 30, 1920. Serial No. 377,812.

To all whom it may concern:

Be it known that I, ELMER E. HUNT, a citizen of the United States, residing at Chicago, in the county of Cook and State of Illinois, have invented certain new and useful Improvements in Window-Ventilators and the like, of which the following is a specification.

The present invention has to do with improvements in window ventilators of that type in which a glass pane or guard of other material is located across the window sill from side to side of the window casing, and said pane slanting upwardly, so that when the lower sash is raised for ventilation purposes, the draft is thrown toward the upper part of the room.

Naturally when the window is opened dust and particles of foreign matter will be carried into the room with the current of air.

The main object of the present invention is to provide, in conjunction with ventilators of this type, a guard or means for preventing the carrying of such dust or foreign matter into the room by catching the same as the air passes up over the ventilator, so that the dust will be compelled to fall back toward the outside.

Another object of the invention is to provide, in arrangements of this type, a dust-guard which can be very readily attached or detached from the ventilator itself, thus making it possible to easily remove the dust guard from the ventilator when the window is to be washed or cleaned, or when the ventilator sheet is to be removed from the window casing. The dust guard is also so formed that it can be easily applied to ventilators already installed.

Other objects and uses of the invention will appear from a detailed description of the same which consists in the features of construction and combinations of parts hereinafter described and claimed.

In the drawings—

Figure 1 shows a fragmentary perspective view of the lower portion of a window casing having applied thereto a ventilator embodying the features of the present invention, the lower window sash being partly raised;

Fig. 2 shows a fragmentary view of the edge of the ventilator pane having applied thereto a dust guard embodying the features of the present invention;

Fig. 3 shows a fragmentary section taken on the line 3—3 of Fig. 2, looking in the direction of the arrows; and

Fig. 4 shows a bottom perspective fragmentary view of the end portion of the dust guard.

In the figures I have shown the features of the present invention as applied to a window casing 5 having the lower sash 6. The plates or end members 7 and 8 are fastened to the lower side portions of the window casing 5 in the manner which is well understood in the art. These members 7 and 8 being provided with slots extending in more or less vertical fashion to receive the end portions of the ventilator sheet or pane 9. This pane is generally made of glass, either plain or wire glass, and either clear or flor- entine, or other fancy finish. The sheet or pane 9 may be removed from the members 7 and 8 by sliding it up in the slots or grooves aforesaid. Such removal is frequently necessary or desirable when the windows are to be washed in order to prevent possible breakage of the pane 9. The air entering beneath the sash 6 travels up over the outside face of the pane 9 and over its upper edge. In order to trap dust and other foreign matter, I have provided a guard

illustrated in detail in Figs. 2, 3, and 4. Said guard is preferably made of sheet metal of length substantially the same as the distance between the members 7 and 8; and said sheet metal is folded so as to provide a pair of substantially parallel channels 11 and 12. The channel 11 is of proper width to receive the upper edge of the glass pane 9; and said channel comprises the side walls 13 and 14. Ordinarily these will be bent in such fashion as to grip the glass pane between them with a fair amount of pressure, so that the guard will retain its position on the pane against any drafts of air or other tendency toward removal. In this way the guard is held in place with a spring pressure, but may be easily removed, if desired.

The channel 12 is formed between the flanges 14 and 15. The flange 15 may, in some cases, be eliminated, but ordinarily the dust or other matter will be trapped much more fully and effectively by making use of the flange 15. In this way the air currents will circulate substantially as shown by the arrows in Fig. 3, with the tendency to throw the dust back and down along the outer face of the pane 9, so that it will collect on the

- window sill outside of said pane, whence it may be removed from time to time, the pane 9 being slid up with respect to the members 7 and 8 if necessary for such purpose.
- 5 It will be observed that upon the application of a sufficient lifting pressure to the flange 15, there will be a tendency to spread the flange 14 away from the glass pane, thus making it easier for the operator to remove the guard than would otherwise be the case.
- 10 By the use of sheet metal, such as sheet steel or the like, sufficient spring action may be secured to insure a very easy insertion and removal of the guard.

I claim:

The combination with a ventilator plate of a dust guard removably mounted on the upper edge of said plate, said dust guard comprising a strip of sheet metal folded to provide a downwardly facing channel of width 20 to firmly embrace the upper edge of the plate, and also to provide an outwardly extending downwardly facing lip for the entrapment of dust or other foreign matter carried by the air flowing up over the outside face of the plate, substantially as described.

ELMER E. HUNT.
